Attorney

UNITED STATES PATENT OFFICE

GEORGE KARMANN, OF STANTON, NEBRASKA

DRAFT EQUALIZER

Application filed July 16, 1929, Serial No. 378,764. Renewed March 28, 1931.

This invention relates to an improvement in draft equalizers, and the primary object of the invention is to provide a device which may be attached to the tongue or pole of a vehicle so as to permit the use of an unequal number of horses on either side of the pole, and yet maintain an equal forward pull upon the pole.

A still further object of the invention is to provide a draft equalizer, so constructed as to be capable of use with either three or four horses, to be disposed on either side of the pole or vehicle tongue in an unequal number, by use of a part or the entire equipment as is desired.

A further object of this invention is to provide a draft equalizer which will be of simple and inexpensive structure, capable of use with any desired number of horses, will be strong, durable, practical and efficient in use, and otherwise well adapted to the purpose intended.

Further objects and advantages of the invention will become apparent to the reader during a study of the following description taken in connection with the accompanying drawings, wherein:

Figure 1 is a top plan view of my entire device.

Figure 2 is a top plan view of a modified form of my device.

Figure 3 is a detail sectional view taken on line 3—3 of Figure 1.

Figure 4 is a detail perspective of one of the connecting bars, and

Figure 5 is a detail perspective of one of the draft levers.

With reference to the drawings, attention is first directed to Figure 1 wherein is illustrated one embodiment of my invention capable for use when it is desirous of employing four horses in the draft. With reference to Figure 1, the numeral 5 designates a primary draft lever adapted for association with the forward end of a vehicle tongue or pole. The lever 5 is provided with an outward bend 6, and one end of the lever 5 is provided with a pair of spaced openings 4 to permit it fastening to the vehicle tongue or pole by means of bolts or other suitable fastening means,

while the extreme end of the curved portion 6 of the lever 5 is offset as at 7 and is provided with an opening 8 on the offset portion for a purpose to be hereinafter fully set forth. Pivots connected to the under face 55 of the lever 5 as at 9 is a bar 10, on the outer end of which bar 10 is a link 11 secured thereto as at 12 and the outer end of the link 11 carries a whiffle tree 13 for a single horse. A second bar 14 is pivoted intermediate its ends to one end of the bar 10 as at 15. The inner end of the bar 14 is offset as at 16 and extends transversely of the lever 5, and the inner end of said bar 14 being provided with an opening 17 to permit of its connection to 60 the draft lever 5 by means of a link 18 passing through an opening 17 in the bar 14 and the opening 18 in the lever 5. Connected as at 19 to the opposite end of the second bar 14 is a secondary draft lever 20, extending at 70 right angles to the bar 14. The secondary draft lever 20 is also outwardly curved as at 21, and the extremity of the curved portion 21 being offset as at 22 to provide a projection 23 for a purpose to be hereinafter 75 set forth. The lever 20 is also offset as at 24 adjacent its pivotal connection 19. A bar 25 is pivotally connected intermediate its ends as at 26 to the lever 20, and one end of the bar 25 is also provided with a link 27 80 secured thereto as at 28, said link carrying a whiffle tree 29 for a single horse, and the whiffle tree 29 being preferably disposed in alignment with the primary draft lever 5. A bar 30 of a structure similar to the bar 14 is 85 pivoted intermediate its ends to the other end of the bar 25 as at 31, and said bar 30 being offset as at 32 to extend transversely of the secondary lever 20 and is connected to the extension 23 of the lever 20 by means of a link 33. A link 34 is secured to the free end of the bar 30 and extends at right angles thereto, and secured to the outer end of the link 34 is an equalizer 35 carrying whiffle trees 36 for two horses. 90

In Figure 2 I have shown the device minus the primary lever 5, bar 10, together with the second bar 14 so that if it is desirous of using but three horses, that embodiment of 100

the invention as illustrated in Figure 2 may be used for this purpose.

In Figure 1 I have illustrated that embodiment of my invention for use for four horses, and it will be readily apparent that the device is attached to the forward end of the vehicle tongue, the primary draft lever 5 being rigidly secured thereto as before described, the device is so arranged as to equalize the draft between the four horses, two of said horses being disposed on one side of the tongue, one in direct alinement with the tongue, and one on the other side of the tongue, and it will be observed that when the horses are secured to the whiffle trees and started, the strain will come directly to the levers 5 and 20, but as the bars 10 and 25 are pivotally connected to the respective lever and also pivotally connected to the bars 14 and 30 respectively, which bars are in turn connected to the respective levers, the horses may readily adjust themselves and the draft be perfectly equalized.

When it is desired to use but three horses, only that portion of the device as illustrated in Figure 2 is used, and again it will be observed that when the horses are secured to the whiffle tree and then started the strain will come directly to the secondary lever 20 to which is pivotally connected the bar 25 which has the bar 30 pivotally secured thereto and one end of the bar 30 being secured to the lever 20 to permit an easy adjustment of the horses and equalize the strain between the two horses on one side and the single horse on the other.

In view of the apparent simplicity of the device, and the ease with which it may be readily understood by those skilled in the art, it is believed that a more detailed description of the device is unnecessary.

From the foregoing therefore it will be seen that I have provided a simple, practical and efficient draft equalizer which can be easily adapted for use for three or four horses, and wherein the strain will be evenly disposed between the animals.

While I have herein shown and described certain structural detail features of my invention, it is to be understood that certain changes may be made therein, coming within the spirit of the invention as described, and the scope of the appended claims.

Having thus described the invention, what I wish to claim as new and desire to secure by Letters Patent is:—

1. A draft equalizer comprising a main draft lever adapted to be secured at one end thereof to a draft tongue of a vehicle, said lever at its other end being curved outwardly and the extremity of said curved end being offset, a bar pivoted intermediate its ends adjacent the curved portion of said lever, said bar being provided at one end with means for attachment to a draft animal, a second

bar pivoted intermediate its ends to the first mentioned bar, said second bar at one end thereof being offset and adapted to extend transversely of said lever, means for connecting the offset ends of said second bar and said lever together, an evener mounted on the other end of said second bar, and whiffle trees carried by said evener.

2. A draft equalizer comprising a lever adapted to be secured at one end to the draft tongue of a vehicle, said lever at its free end terminating in a curved portion, the terminal of said curved portion being offset, said lever, intermediate its ends being offset, a bar pivoted inwardly from one end thereof to said lever, adjacent the curved end of said lever, a link secured at one end to the other end of said bar, a whiffle tree secured to the free end of said link, a second bar pivoted intermediate its ends to the first referred to one end of the first mentioned bar, said second bar being offset intermediate its ends, and having its offset portion extending transversely of said lever, a link connection between the offset ends of said second bar and said lever, a third link secured at one end to the free end of said second bar, an equalizer secured intermediate its ends to the free end of said third link, and whiffle trees carried by said evener.

In testimony whereof I affix my signature.
GEORGE KARMANN.
